CLAIM

The ornamental design for a ventilated food container, as shown and described.

DESCRIPTION

FIG. 1 is a top perspective view of the ventilated food container showing a ventilation feature in a closed condition;

FIG. 2 is a top perspective view of the ventilated food container showing a ventilation feature in an opened condition;

FIG. 3 is a top view of the ventilated food container shown in FIG. 1;

FIG. 4 is a top view of the ventilated food container shown in FIG. 2;

FIG. 5 is a front side view of the ventilated food container shown in FIG. 1;

FIG. 6 is a back side view of the ventilated food container shown in FIG. 1;

FIG. 7 is a bottom view of the ventilated food container shown in FIG. 1;

FIG. 8 is a left side view of the ventilated food container shown in FIG. 1; and,

FIG. 9 is a right side view of the ventilated food container shown in FIG. 1.

The broken lines shown in a semi-circular C-shaped configuration represent perforations which are part of the claimed design.

The broken lines shown as being in straight configuration illustrate portions of the ventilated food container that form no part of the design.
